COMBINATION SQUARE AND LEVEL

Cono Brower, Watertown, S. Dak.

Application July 2, 1956, Serial No. 42,109

Term of patent 7 years

(Cl. D52—1)

Figure 1 is a side view of a combination square and level showing my new design.

Figure 2 is a top plan view thereof.

Figure 3 is an end view of the combination square and level as shown in Figure 1.

The opposite side of the combination square and level is the same in appearance as the side disclosed in the drawing.

I claim:

The ornamental design for a combination square and level, as shown and described.
